UNITED STATES PATENT OFFICE.

CHARLES L. BEERS, OF SCRANTON, PENNSYLVANIA.

FIRE-BOX-LINING SUPPORT.

SPECIFICATION forming part of Letters Patent No. 674,724, dated May 21, 1901.

Application filed December 29, 1900. Serial No. 41,470. (No model.)

To all whom it may concern:

Be it known that I, CHARLES L. BEERS, a citizen of the United States, and a resident of Scranton, in the county of Lackawanna, in 5 the State of Pennsylvania, have invented new and useful Improvements in Fire-Box-Lining Supports, of which the following, taken in connection with the accompanying drawings, is a full, clear, and exact description.

This invention relates to the fire-boxes of stoves and ranges, and has special reference to the devices employed for supporting the fire-brick linings in said fire-boxes.

The object of the invention is to provide a 15 supporting device which shall be simple and inexpensive in construction, adapted to be readily applied to any stove or range, and adjustable to varying depths of fire-boxes; and to that end the invention consists in the combination, with the movable grate and fire-box lining, of plates disposed in juxtaposition to and parallel with the walls of the fire-box and provided with ledges for supporting the fire-brick lining, said ledges being situated above 25 and extending over part of said movable grate, and means for adjusting said plates to and from the grate.

In the accompanying drawings, Figure 1 is a top plan view of a fire-box provided with 30 my improved means for supporting the fire-brick lining. Fig. 2 is a vertical transverse section of the same. Fig. 3 is a detached perspective view of my preferred construction of the fire-brick-lining supporter. Fig. 35 4 is a plan view of the blank from which said supporter is formed. Fig. 5 is a face view of a modification of my invention, and Fig. 6 is an end view of the same.

Similar letters of reference indicate corresponding parts.

C represents the fire-box of a stove or range, and D is the grate, which may be of any suitable shape. The inner walls of the fire-box above the grate are protected by fire-brick linings, as indicated by dotted lines 11 in Fig. 2 of the drawings.

In some fire-boxes the front is protected by a water-chamber covering the front wall of the fire-box and dispensing with the fire-brick lining thereat. In cases where the fire-box is de-

prived of such water-chamber the fire-brick linings *ll* are applied to the front as well as to the back of the fire-box, as shown in Fig. 2 of the drawings. These linings have heretofore been supported upon a horizontal 55 frame which was supported upon lugs on the front and rear walls of the fire-box and upon the tops of the grate-hanger boxes *a a*. In the use of such supporting-frame it has been found that it is liable to sag onto the grate 60 and prevent the same from turning. To obviate this defect, I employ a plate *b*, which is provided at its base with a ledge *c*, constituting the seat of the fire-brick lining. This plate, with its ledge, I preferably form of a 65 wrought-iron blank *B*, (shown in Fig. 4 of the drawings,) which blank I bend along the dotted line *c'* at the requisite angle to form the ledge *c*. (Shown in Fig. 3 of the drawings.)

To guard more effectually against the sagging of the ledge *c*, I form the central portion of the plate *b* with a vertical extension, as shown at *b'*, and perforate said extension, as shown at *e*, for the reception of bolts or 75 other suitable devices for fastening said plate to the wall of the fire-box. Said perforations may be made to secure the plate *b* in proper position to carry the ledge *c* in its requisite proximity to the subjacent grate *D*, as shown 80 in Fig. 2 of the drawings. Consequently the said plate, with its ledge, is adapted to be applied to fire-boxes of varying depths.

The aforesaid construction dispenses with the usual false back of the fire-box. I do not, 85 however, limit myself to the construction shown in Fig. 3 of the drawings, inasmuch as my improved fire-brick supporter may be constructed as shown in Figs. 5 and 6 of the drawings, in which the ledge *c* is formed separate from the plate *b* and is secured thereto by angle-irons *f f*, riveted to said parts. In this case the plate *b* is reinforced by a hanger or vertically-elongated plate *h*, formed at its base with a horizontal offset *h'*, upon which 95 the center of the ledge *c* rests. This hanger and its offset are fastened, respectively, to the plate *b* and to the ledge *c* by means of rivets *i i*.

The hanger is perforated, as shown at *t t*, 100

for receiving through the perforations the bolts by which the hanger is fastened to the wall of the fire-box.

What I claim is—

- 5 In a stove or range, the combination with the movable grate and fire-brick lining, of plates disposed in juxtaposition to and parallel with the walls of the fire-box and provided with ledges for supporting the fire-brick lin-

ing, said ledges being situated above and extending over part of said movable grate and means for adjusting said plates to and from the grate. ¹⁰

CHARLES L. BEERS.
